(57) **CLAIM**

The ornamental design for a free-angle camera mount, as shown and described.

DESCRIPTION

FIG. 1 is a left front perspective view of a free-angle camera mount showing our new design;

FIG. 2 is a front elevation view thereof;

FIG. 3. is a back elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a front perspective view thereof; and,

FIG. 9 is a side perspective view thereof.

The broken lines in the drawings form no part of the claimed design.

1 Claim, 9 Drawing Sheets
